UNITED STATES PATENT OFFICE

DANIEL THEW WRIGHT, OF WASHINGTON, DISTRICT OF COLUMBIA

HEATER ATTACHMENT

Application filed June 12, 1930. Serial No. 460,676.

My invention relates to broiler attachments for heating stoves.

The principal object of the invention is to provide a broiler hood attachment which may be readily applied to and detached from a conventional type of portable open hearth gasoline stoves now in wide use.

Another object is to provide a broiler hood attachment which will not obstruct or interfere with the escape of fumes or products of combustion.

Other and more specific objects and advantages of the invention will be apparent as the specification is considered in connection with the accompanying drawing, in which:

Figure 1 is a front perspective view of a gasoline heater with the broiler hood attached thereto, the gravy tray being shown in partially withdrawn position;

Figure 2 is a rear perspective view of the broiler hood removed, showing conventional broiler frame attached to the broiler hood; and

Figure 3 is a vertical sectional view of the broiler hood partly broken away.

Referring more particularly to the drawing wherein the same reference characters indicate like parts in all the figures, 1 represents a gasoline heater of old and well known construction comprising a lower or base portion 2 which houses the gasoline tank or container 3, and an upper or hearth portion 25, in which the burners 7 are mounted. It will be noted that the side walls 4 and 5 and the rear wall 6 of the heater extend upwardly from the base portion 2 to provide the substantially U-shaped open hearth upper portion 25 previously mentioned, and in which the vertically disposed burners 7 are suitably mounted.

It will also be noted that the front wall 8 of the heater does not extend upwardly beyond the lower ends of the burners, and that the reticulated top member 25' of the heater does not extend at its intermediate forward edge to the front of the heater. Consequently the burners, 7, are enclosed on but three sides, thus leaving the top and front substantially open. Supporting posts 9 and 10, suitably secured to the heater adjacent the for-

ward edges of the side walls 4 and 5, are provided with ornamental knobs 9' and 10' at their upper ends which are utilized in a manner hereinafter described.

A broiler hood 11, preferably of sheet metal, and of substantially U-shape in horizontal cross section is employed to cover the front opening 12 of the heater when it is desired to use the latter as a broiler. This hood comprises a bottom wall 12', front wall 13 and side walls 14 and 15, the back of the hood being entirely open with the exception of a narrow strip or cross piece 16 which connects the rear lower edge of the side members to each other.

When the hood 11 is in use, the rear edge of the side members 14 and 15 thereof lie adjacent the respective posts 9 and 10 of the heater, and the extremities of the rear strip 16 will also rest in proximity to or against these posts. Hooks 17 and 18 pivoted to the upper rear corners of side members 14 and 15, when engaged over the respective knobs 9 and 10 of the heater, hold the hood securely in place. It will also be noted that the lower portion of the hood will be held in snug contact with the lower front portion of the heater by force of gravity. A drip pan 26, the purpose of which will be apparent, is slidably mounted upon the bottom 12 of the hood, and may be withdrawn through opening 27 formed in the side wall 14 of the hood.

The meat to be broiled is placed in a broiler frame 19, illustrated by chain dotted lines in Figure 2. This frame comprises the two hinged sections 20, each provided with handles 21, adapted to be maintained in closed position by ring 22, all of said parts being old and well known in the art. A hook 23 having a plurality of prongs 23' is pivoted to the top edge of the front wall 13 of the broiler hood, and is adapted for engagement either with the ring 22 or the top of the broiler frame for supporting the latter in desired adjusted position toward or away from the burners 7. The bottom of the broiler frame rests upon the bottom of the gravy tray 26, and the frame can be readily moved by tilting or sliding movement.

It will be obvious that by increasing the

number of prongs 23', the range of lateral adjustment of the broiler frame with respect to the burners will be correspondingly increased. When the meat has been broiled, the 5 broiler frame can be readily moved away from the burners by lifting the hook out of engagement with the broiler and pulling the latter away from the burners. It will also be noted that the form of hook fastener employed 10 permits the operator to readily release and turn the broiler frame to present both sides of the meat in turn to the flame.

As the top of the hood is entirely open, thus 15 permitting the escape of the steam etc., the broiling effect is not interfered with, as will be readily understood.

Having thus described my invention what I claim is:

1. A broiler hood or casing for open hearth 20 stoves comprising a front wall, side walls and a bottom wall, and open at its top, means carried by the hood for detachably securing the same to the front of the stove and pronged means pivoted to the front wall for engaging the top of a broiler frame and detachably supporting and maintaining said frame in adjusted position therein relative to said front wall and the front of the stove.
2. A broiler hood for open hearth stoves 25 comprising a front wall, side walls, and a bottom wall and open at its top, a drip pan removably supported on said bottom wall, means carried by the hood for detachably securing the latter to the front of the stove, 30 means secured to the front wall having members at its end for selectively engaging the top of a broiler frame and detachably supporting and maintaining said broiler frame in adjusted position towards or away from the front 35 wall and the front of the stove.

In testimony whereof I affix my signature.

DANIEL THEW WRIGHT.
